UNITED STATES PATENT OFFICE.

JAMES M. MERRITT, OF HOMER, MICHIGAN, ASSIGNOR OF ONE-HALF TO
BENJAMIN F. GOODRICH, OF SAME PLACE.

DESIGN FOR A CIGAR-HOLDER.

SPECIFICATION forming part of Design No. 24,449, dated July 2, 1895.

Application filed May 18, 1895. Serial No. 549,837. Term of patent 7 years.

To all whom it may concern:

Be it known that I, JAMES M. MERRITT, a citizen of the United States, residing at Homer, county of Calhoun, and State of Michigan, have invented and produced a new and original Design for a Cigar-Holder, of which the following is a specification, reference being had to the accompanying drawings, which form a part of this specification, showing a part thereof.

Figure 1 is a view in side elevation of a cigar-holder, showing my design. Fig. 2 is a similar elevation of the same at right angles to Fig. 1.

The leading feature of my design consists in two arms A A', flattened toward one end thereof, as indicated at a a, one extremity of the holder being formed into a terminal disk convexed on its outer surfaces. (Indicated at a'.) Above the flattened portions a a said arms are rounded on their outer surfaces, as indicated at a² and a³, the rounded surfaces extending longitudinally of the arms upward toward the opposite extremity of the holder,

the said arms, toward their extremities opposite said disk, being curved outwardly or made circular in their outer contour, as indicated at a⁴ and a⁵. The extremities of the arms above the said curve or circular portions a⁴ a⁵ are flattened and are adjacent the one to the other, as indicated at a⁶ a⁷.

My design thus embraces the arms A A', having the disk a' at one end thereof, the flattened portions a a above the disk, the rounded portions a² a³ above the flattened portions, the circular portions, as at a⁴ a⁵, of said arms above the rounded portions a³ a⁴, and the flattened portions a⁶ and a⁷ at the terminals of the arms opposite the disks.

What I claim is—

The design for a cigar holder herein shown and described as set forth.

In testimony whereof I sign this specification in the presence of two witnesses.

JAMES M. MERRITT.
